(57) CLAIM

The ornamental design for a combination snap hook and lighter, substantially as shown and described.

DESCRIPTION

FIG. 1 is a top, front and left side perspective view of the combination snap hook and lighter in a position of use

FIG. 2 is a left side elevational view of the embodiment of FIG. 1, with its ignition device in disposed position

FIG. 3 is a right side elevational view of the embodiment of FIG. 1, with its ignition device in disposed position

FIG. 4 is a top plan view of the embodiment of FIG. 1

FIG. 5 is a bottom plan view with the embodiment of FIG. 1

FIG. 6 is a front view of the embodiment of FIG. 1; and, FIG. 7 is a rear view of the embodiment of FIG. 1.

The broken line environmental showing is for illustrative purpose only and forms no part of the claimed design.
